UNITED STATES PATENT OFFICE.

ELBERT O. HASKINS, OF RUTHERFORD, NEW JERSEY, ASSIGNOR TO RICHMOND
RADIATOR COMPANY, A CORPORATION OF DELAWARE.

SECTIONAL BOILER.

1,391,381.

Specification of Letters Patent. Patented Sept. 20, 1921.

Application filed July 18, 1917. Serial No. 181,190.

To all whom it may concern:

Be it known that I, ELBERT O. HASKINS, a citizen of the United States, and resident of Rutherford, in the county of Bergen and 5 State of New Jersey, have invented certain new and useful Improvements in Sectional Boilers, of which the following is a specification.

My invention relates in general to a sectional boiler particularly of the round type used for supplying steam or hot water for house heating systems.

One of the objects of my invention is to provide a simple form of boiler of the class 15 described, which will attain high efficiency and in which there will be a relatively small amount of resulting ash. One means by which this object is attained is to provide the furnace with a magazine fuel feed so designed that the air supply for supporting the combustion is caused to pass progressively from the coldest to the hottest portions of the burning zone of solid fuel and is then passed directly into a gas-combustion 25 chamber designed to completely oxidize the hydro-carbonaceous fuel matter generated by the burning of the solid fuel.

Another object of the invention is to provide such a device with water containing 30 spaces so disposed as to extract the greatest possible amount of heat from the combustion zones and at the same time disposed so as to have their minimum cooling effect upon the combustion taking place in the zones.

Still another object of the invention is to provide an attachment constructed to constitute a separate article of manufacture and designed to be assembled with certain conventional forms of upright boilers in such a 40 manner so as to convert such boilers into a device of the class described.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter 50 set forth and claimed.

Referring to the accompanying drawings:

Figure 1 is a perspective view of a preferred embodiment of my invention with 55 parts broken away; and

Fig. 2 is a similar view of the attachment designed to be added to a conventional boiler to constitute the combustion chamber of the reconstructed device shown in Fig. 1.

In the following description and in the 60 claims, parts will be identified by specific names for convenience of expression but they are intended to be as generic in their application to similar parts as the art will permit.

In the drawings there is shown an ash-pit section 3 provided with a grate 4 upon which section is mounted the hollow wall fire pot or box section 5, which forms a relatively deep fire pot. The ash-pit section is provided with the usual slide opening 3^a to permit some air to pass through the grate especially when first firing the fuel, but it is to be understood that no dependency is placed upon the supply of air passing 70 through the grate to maintain combustion. There is also shown in the drawing an intermediate water section 6, illustrative of several such sections usually assembled in devices of large capacity, and a dome section 7. These sections are designed to fit one upon the other to form a built up unit as is usual in one well-known form of sectional boilers.

The attachment shown in Fig. 2 has its 85 upper portion disposed between the water section 6 and the fire box section 5 to constitute an additional water section. This attachment is funnel shaped with an upper band section 8 adapted to overlap the top of 90 the section 5 and with its outer side constituting a continuation of the outer side of the section 6. The band is supported from and spaced from the upper edge 9 of the section 5 by means of a pair of oppositely 95 disposed depending supports 10 connected with the section 5 by means of nipples 10^a which are received in sockets 11 formed in the edge 9. The intermediate portion 12 of the attachment depends inwardly from the 100 band 8 toward the center of the upper portion of the section 5 and leads into a cylindrical wall 13 which depends centrally within the section 5 to a position adjacent to and spaced above the grate. The wall 13 is 105 spaced from the inner wall of the section 5 so as to form an annular coal chamber 14 therebetween. The attachment is hollow to provide a gas combustion chamber 15 having its lower end 16 opening into the fire 110

space adjacent the grate and having its upper end 17 discharging through apertures 18 in the water section 6. In order to prevent a too rapid supply of air through the grate 5 directly into the chamber 15 the portion 4^a of the grate directly below the end 16 is partly closed. The apertures 18 open into the centrally disposed discharge conduit 19 leading out of the boiler as is usual with 10 devices of this character. The device as thus far described in connection with the attachment is complete but under some conditions of use it is desired to introduce air directly into the chamber 15 so as to insure a 15 sufficient supply of air to support the complete combustion of the gases therein. For this purpose the drawing is shown to contain an auxiliary air supply pipe 19^a leading from the outside directly into the lower end 20 16 of the gas combustion chamber. Further the lower end of the wall 13 is shown to be slotted to provide passageway 19^b to permit the passage of some of the air and gases generated in the fire box directly into 25 the combustion chamber without having to pass down to the bottom of the wall 13, but it is to be understood that no dependency is placed upon these passageways to supply fuel to the combustion chamber 15.

30 A tub-like shell 20 surrounds and is spaced from the section 6, drum 7 and underlaps the band 8. The shell coacts with the outer walls of these members to form a fuel magazine 21 provided with a plurality of fuel inlet openings 22 in the upper wall 23 of the shell. These openings are adapted to be closed by means of hinged flap doors 24, so as to prevent the entrance of air through the openings 22.

40 The lower edge of the shell 20 is spaced from the portion of the attachment so as to provide a circular inlet 25 opening from the magazine into the upper portion of the fuel space 14. The shell is supported in 45 spaced relation from the top 9 of the section 5 by means of a flat pan 26 spaced from the bottom portion of the shell so as to provide an air passageway or wind belt 27 leading into the chamber 14 just below the fuel entrance 25. The admission of air to the passageway 27 is controlled by flap dampers 28.

50 It is understood that the fire box section 5 and the attachment are double walled to provide water containing chambers 29 in fluid 55 communication through the water tight connections provided by the push nipples 10^a. Similarly the water chamber of the attachment is in fluid communication with the water chamber 30 of the water section 6. In 60 order to facilitate the movement of the water in the chamber 29 of the attachment a bypass tube 30 connects the upper with the lower portion of this chamber.

65 By this construction the coal in the fuel chamber 14 is inclosed within the water

walled section 5 and surrounds the water walled pipe 13 so that the water is brought close to the burning coals but not in such masses as would tend to cool the coals. The draft is regulated normally by opening one 70 or more of the dampers 28 as desired. When an additional draft is desired the slide 3^a may be opened. The air from the wind belt 27 passes downwardly through the ignited fuel in the chamber 14 where it is gradually heated to or even above the combustion temperature. This burning fuel is disintegrated and passes with the surplus heated air into the open bottom chamber 15 which has little if any solid fuel therein. In this 75 respect the device is a gas generator. The preheated air combines with the free gaseous hydrocarbon fuel present in the chamber and there results a complete combustion of the fuel before the products are finally 80 passed out through the discharge conduit 19. The under surface of the water section 6 constitutes a reflecting dome to obstruct the free passage of the combustible products out of the combustion chamber 15 and thus 85 tends to insure a complete combustion in the chamber. The highest temperature is present in the upper portion of the combustion chamber, and it is at this place where the greatest heat disengaging surface 90 for the water is exposed to the chamber.

95 By means of a device of this character even soft coal can be used without generating any material amount of smoke. The coal is entirely consumed without the use 100 of any artificial draft creating means, thus economizing in fuel consumed even in the small household furnace herein disclosed.

105 As the combustible products are first turned into a gas and this gas burned the device has all of the advantages of a gas burner and further the gas combustion zone is protected by the surrounding gas generating zone, thus tending to conserve the intense heat produced in the gas chamber.

110 The device needs but little attention after the fuel magazine is filled for the device acts as a self feeder gradually lowering fuel into the fire box as the ashes drop down through the grate.

115 While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

120 Having thus described my invention, I claim:

1. In a sectional boiler, the combination with a fire box section and a grate, of a gas combustion chamber disposed within said fire box section and having an open lower 130

end above the grate, the space between the lower open end of the chamber and the fire box section adapted to contain the fuel and means for admitting air to the top of the 5 fuel in said space.

2. In a sectional boiler, the combination with a fire box section and a grate, of a gas combustion chamber disposed within said fire box section and having an open lower 10 end above the grate, the space between the chamber and the fire box section adapted to contain the fuel, and means for admitting air to the top of said space, the upper end of said chamber being open and adapted to 15 constitute the discharge end for the products of combustion in said chamber, means positioned between the grate and the lower open end of the chamber for preventing a too rapid supply of air through the grate directly into the chamber.

3. In a sectional boiler, the combination with a hollow fire box section adapted to inclose a bed of burning coals and containing a continuous wall of water and a grate, of 25 a gas combustion chamber disposed entirely within said fire box section and having an open lower end, the space between the open end of the chamber and the fire box section adapted to contain the bed of burning coals, 30 manually controlled, means for admitting air to the upper part of said space, and a magazine opening down into said space adjacent said manually actuated air controlling means.

35 4. In a sectional boiler, the combination with an ash pit section fire box section, a water section and a dome section superposed in order, of a gas combustion chamber section supported on said fire box section and 40 provided with an extension depending into the fire box section and terminating above the ash pit section and spaced from to form a fire space means for supplying combustion supporting air to the top of the fuel in the 45 fire-box section.

5. In a sectional boiler, the combination with an ash pit section normally closed to the admission of combustion supporting air and provided with a grate, a fire box section 50 disposed thereon, of a gas combustion chamber section supported from the fire box section and provided with an extension depending centrally into the fire box section to form an annular coal chamber between the 55 fire pot section and the extension, said chamber having a lower open end positioned above the grate and adapted to receive the gaseous fuel generated by the burning coals in the fire box section, the space between the

60 lower open end of the chamber and the grate constituting a fire space constantly open to the annular coal chamber, means for supplying combustion supporting air to the top of the fuel in the fire-box section.

65 6. In a sectional boiler, the combination

with a fire box section, a water section and a dome section superposed in order, of a combustion chamber section supported by said fire box section and provided with an extension depending into the fire box section and 70 spaced therefrom to form a fire space, means for supplying fuel to the top of said space, a magazine section surrounding said water section and said dome section and opening into said fire space, said magazine section 75 provided with a fuel supplying opening and a door for closing said opening to prevent the combustion level of the fuel from raising up into the magazine.

7. In a sectional boiler, the combination with a fire box section; a water section and a dome section superposed in order, of a combustion chamber section supported by said fire box section and provided with an extension depending into the fire box section and 80 spaced therefrom to form a fire space, means for supplying fuel to the top of said space, a magazine section surrounding said water section and said dome section and opening into said fire space, said magazine section 85 provided with a fuel supplying opening, a door for closing said opening and for preventing air from circulating through said magazine, and a draft door positioned below said magazine for regulating the air supplied to said fire space.

8. In a down draft boiler, the combination of a fire box provided with a burning fuel supporting grate, a combustion chamber disposed in said fire box and having an 100 open end positioned above the grate adapted to receive gas from the fire box the portion of the grate below the open end of the combustion chamber being partly closed, an air intake spaced above said grate and above 105 the fire box and entirely surrounding the top of the fire box, and means for directing the air down through said fire box and up through said combustion chamber.

9. An article of manufacture comprising 110 a section of a sectional boiler and including a flat band provided with means for supporting the same in place horizontally in a boiler and including a hollow depending extension from the band constituting a gas combustion chamber, said band and extension being double walled to provide a water containing chamber inclosing the gas combustion chamber, said article provided with a supporting means constituting a conduit adapted to place said water containing chamber in fluid communication with a 115 lower section.

10. In a device of the class described, the combination of a fire box section, including 125 a completely closed cylindrical wall, an attachment supported from said fire box section constituting a gaseous fuel combustion chamber and having a portion depending into and spaced from said fire box section 130

to form a solid fuel combustion chamber, a water section disposed on said attachment, a shell surrounding said water section and coacting therewith to form a fuel magazine, 5 said magazine opening into the space between the fire box section and the depending portion of said attachment and means above said closed wall for admitting combustion-supporting-air to the upper portion of said space.

11. In a device of the class described, the combination of a fire box section, an attachment supported from said fire box section and having a portion depending into and 15 spaced from said fire box section, a water section disposed on said attachment, a shell surrounding said water section and coacting therewith to form a fuel magazine, said magazine opening downwardly into the 20 space between the fire box section and the depending portion of said attachment, an inlet for the air positioned between the fire box section and the magazine, said shell provided with a fuel supply opening and means 25 for closing said opening to prevent air passing therethrough.

12. In a device of the class described, the combination of an upstanding cylindrical fire box section opened at top and bottom 30 and otherwise closed, an attachment supported from said fire box section and having

a portion depending into and spaced from said fire box section to form a long annular solid fuel combustion chamber, a water section disposed on said attachment, a shell 35 surrounding said water section and coacting therewith to form a fuel magazine, said magazine opening into the space between the fire box section and the depending portion of said attachment, and a pan disposed between said shell and fire box section constituting an air passageway for conducting the combustion-supporting-air into the upper portion of said fire box section. 40

13. In a furnace, the combination with a 45 fire box provided with a fuel support adapted to contain a bed of burning fuel, means positioned above the bed for supplying combustion-supporting-air thereto, of a hollow member, extending below the level of the 50 fire bed, having a lower open end positioned above the support and adapted to receive the products of combustion from said fire bed, said fire bed adapted to permit the accumulation of ashes in the lower part thereof and 55 thus prevent the passage of combustion supporting air directly into the hollow member.

Signed at New York city in the county of New York and State of New York.

ELBERT O. HASKINS.
